UNITED STATES PATENT OFFICE.

EDWARD PERCY CORPS, OF NORTHAMPTON, ENGLAND.

TACK-EXTRACTING MACHINE FOR BOOTS AND SHOES.

Application filed December 8, 1919. Serial No. 343,357.

To all whom it may concern:

Be it known that I, EDWARD PERCY CORPS, subject of the King of Great Britain, residing at Northampton, in the county of 5 Northampton, England, have invented Tack-Extracting Machines for Boots and Shoes, of which the following is a specification, reference being had therein to the accompanying drawing.

10 This invention relates to tack extracting machines for use in the manufacture of boots and shoes and the like and has for its object to produce an efficient machine operating on the rotary principle for extracting 15 lasting and similar tacks.

The invention consists of a machine having a rotary extractor device composed of a pair of circular plates clamped together face to face with an intervening space said 20 plates having formed in their opposing faces one or more (conveniently two or three) channels or grooves lying on the chords of the circular plates, the groove or grooves in each plate combining with that or those in 25 the opposite plate to form a passage or passages, the faces of the plates being cut away on the periphery to provide an entrance opening to said passage or passages for the tack heads, said tacks being drawn 30 out of the work in the direction of the axis of the rotating extractor device by the passage or passages in the latter.

A guard and a clearing tool are employed 35 in conjunction with the rotating extractor device as will be hereinafter described.

In particularly describing the invention, reference will be made to the accompanying drawing wherein a concrete form of machine is shown by way of example.

40 In the drawing:—

Figure 1 is a front elevation of the machine.

Figure 2 is an end elevation of the same viewed from the left of Figure 1.

45 Figure 3 shows the inside face of the two plates constituting the rotary track extractor device.

Figure 4 is a side view of the clearing tool.

Figure 5 shows in side elevation (a) front 50 elevation (b) and plan (c) the supplementary guard.

Figure 6 shows the arm for controlling the oscillating guard.

55 Figure 7 shows the stop plate for the arm. Figures 8 and 9 illustrate the operation of the rotary extractor device.

Figure 10 shows the supplementary guard in position for use.

The machine illustrated in the drawing comprises a frame 1 provided with bearings 60 2, 2 carrying a spindle 3 having thereon fast and loose pulleys 4, 5 for driving purposes. The spindle 3 has fast thereon a tack extracting device which is composed of a pair of circular plates 6, 6 (Figures 1, 65 2 and 3) these being clamped together face to face (in Figure 3 they are shown separated) in such a manner that the space between them may be varied, said plates having formed in their opposing faces one or 70 more (conveniently three as shown) channels or grooves 7 disposed on chords of or at an angle relatively to the periphery. When the two plates are in position face to face the channels or grooves in one are in 75 alignment with those of the other plate so that they combine to form passages which pass through the pair of plates. A suitable disposition of these passages is one in which they are substantially straight throughout 80 their length and on chords of a circle of approximately half the diameter of the plates as shown in Figure 3. In the region of the outer end of the passages the plates 6 are cut away on their periphery and also on 85 their opposing faces as shown at 8 in Figures 1 and 3 to provide sufficient opening to admit the head of a tack and allow the latter to be inserted far enough between the plates for the outer sides of the grooves 90 or channels 7 to pass underneath it. The opposing faces of the plates do not meet near the periphery but are separated sufficiently to provide a space 9 (Figure 1) for the shank of the tack without however 95 allowing the head to pass between. Consequently, when, during rotation of the plates in the direction of the arrow, a tack is engaged by the undercut sides of a 100 passage as shown in Figure 8, the head is caused to ride up to the inclined passage 7 as shown in Figure 9 and is thus withdrawn from the work towards the axis of the rotating extractor, the opposing faces of the plates 6 between the passage 7 and 105 periphery of the plates passing on opposite sides of the shank. Those parts of the periphery and sides of the plates which form the entrance of the passages, viz: the parts 10, 10, may be bevelled or suitably formed 110 to assist the extractor getting underneath the head of the tack.

To enable the extractor device to deal with tacks of different thickness, the plates 6 are capable of adjustment relatively to each other to vary the width of the intervening space 9. To this end a series of screws 11 (Figure 3) in one plate may engage with recesses 12 in the opposite plate, an adjustment of the screws varying the separation of the plates. Other means may however, be adopted for this purpose.

The plates 6 are held together by a screw or other clamping means and to clear out any loose tacks from between said plates, a tool in the form of a steel plate 13 (Figures 1, 2 and 4) is situated between the plates and held stationary on a pin 14 so that as the plates revolve, any tack remaining in the passages will be caught by the tool and pushed out of the passage so that it can fall away when the end of the passage comes round. Conveniently the tool is pivoted in the guard about to be described.

The guard conveniently consists of a member 15 bifurcated to pass on each side 25 of the extractor device as shown in Figure 1 and formed to extend partly round the said device as shown in Figure 2. On its lower front side the said member may be furnished with ratchet teeth 16 which engage the work and resist any movement of the latter to which there may be a tendency caused by rotation of the extractor device while withdrawing a tack.

The guard member 15 has a shank 17 35 which is slidable through a rockshaft 18 carried in a bearing 19 on the upper part of the frame 1. The rotary movement of the rockshaft is controlled by an arm 20 (Figures 2 and 6) and a spring 21 the latter being arranged between the free end of said arm and an adjusting device 22. The arm 20 passes through a stop plate 23 (Figures 2 and 7) fixed to the frame. The contact of the arm with the lower end of the slot 40 24 in this plate determines the normal position of the guard while a screw 25 serves as an adjustable stop to limit the yielding oscillatory movement of the guard from the normal position. The shank 17 has thereon a compression spring 26 which allows the guard to yield upwardly. When the work e. g. the insole of a boot, is placed against the guard as indicated by dotted lines in Figure 2 for instance, the whole may be 45 pressed towards the rotating extractor member 6 the guard member 15 yielding by a swinging motion permitted by the rockshaft 18 and spring 21 or by an upward movement permitted by the shank 17 and spring 26 or by both such movements thereby enabling the work to approach sufficiently close to the extractor device for the head of the tack to enter between the plates 6 as aforesaid. Upon removal of the pressure 50 the springs return the guard to its

normal position this being determined by the collar 27 and the plate 23. A set screw or other suitable means (not shown) may be provided to enable the shank to be made fast in the rockshaft to prevent the upward 70 yield of the guard.

There may be provided for use on the guard 15 a supplementary guard 28 (Figure 5) having a plain front surface 29 in which is formed a slot or recess 30. The 75 device is formed to embrace the guard 15 and by means of slots 31 in its sides to fit upon same by engaging with pins 32, (Figures 1 and 2) so as to cover the toothed part 16 as shown in Figure 10. The sides 33 of 80 the device 28 fit upon the outside of the guard 15. This supplementary guard is for use when, to avoid marking the face of the work, it is undesirable to use the toothed part 16 of the guard 15. When in position 85 on the member 15 as shown in Figure 10 the supplementary device 28 provides a plain face 29 for contact of the work, the slot or recess 30 receiving therein the tack to be extracted. In the region of this slot 90 the front 29 is made thin so as to allow the work to be pressed close enough to the rotating extractor device for the head of the tack to enter between the plates 6.

Claims:

1. A tack extracting machine having a rotary extractor device consisting of a pair of circular plates clamped together face to face with an intervening space, said plates having formed in their opposing faces channels lying on chords of said plates, the channel in each plate combining with that in the opposite plate to form a passage, the faces of the plates being cut away on the periphery to provide an entrance opening to 100 said passage for the tack heads, said tacks being drawn out of the work towards the axis of the rotating extractor device by the walls which form its passage in the latter.

2. A tack extracting machine having a rotary extractor device consisting of a pair of circular plates clamped together face to face with an intervening space, said plates having formed in their opposing faces channels lying on chords of said plates, the channel in each plate combining with those in the opposite plate to form passages, the faces of the plates being cut away on the periphery to provide entrance openings to 110 said passages for the tack heads, said tacks being drawn out of the work towards the axis of the rotating extractor device by the walls which form its passages in the latter.

3. A tack extracting machine having a rotary extractor device consisting of a pair of circular plates clamped together face to face with an intervening space, each plate having formed in its inner face a plurality of channels which are substantially straight 125 throughout their length and tangential to a 130

- circle of approximately half the diameter of the plate, the said channels in the opposing plates conjointly forming passages disposed at an angle to the periphery and adapted to 5 engage the tack heads to withdraw the tacks towards the axis of the rotating extractor device, the faces of the plates being cut away on the periphery to provide entrance openings to the passages for the tack heads.
- 10 4. A tack extracting machine having a rotary extractor device consisting of a pair of circular plates clamped together face to face with an intervening space therebetween, channels in the opposing faces, said channels 15 lying on chords of the plates and of the plates conjointly forming passages between the plates adapted to withdraw the tacks towards the axis of the rotating extractor device, and means to adjust the plates relatively to each other to vary the width of the intervening space.
- 20 5. A tack extracting machine having a rotary extractor device consisting of a pair of circular plates clamped together face to face with an intervening space, channels in the opposing faces, said channels lying on chords of the plates and of the plates conjointly forming passages between the plates adapted to withdraw the tacks towards the 25 axis of the rotating extractor device, and a series of screws in one of said plates engaging with recesses in the opposite plate, said screws being adjustable to vary the separation of the plates, for the purpose described.
- 30 35 6. A tack extracting machine having a rotary extractor device consisting of a pair of circular plates clamped together face to face with an intervening space, channels in the opposing faces, said channels lying on chords of the plates and of the plates conjointly forming passages between the plates adapted to withdraw the tacks towards the 40 axis of the rotating extractor device, and a clearing tool to clear the removed tacks from 45 the extractor device.
- 50 7. A tack extracting machine having a rotary extractor device consisting of a pair of circular plates clamped together face to face with an intervening space, channels in the opposing faces, said channels lying on chords of the plates and of the plates conjointly forming passages between the plates for extracting the tacks, and a plate held in a stationary position and situated between 55 the opposing plates adapted to intercept loose tacks and direct same outwards from between the plates.
- 60 8. A tack extracting machine having a rotary extractor device consisting of a pair of circular plates clamped together face to face with an intervening space, channels in the opposing faces, said channels lying on chords
- of the plates and of the plates conjointly forming passages between the plates for extracting the tacks, and a guard member 65 yieldingly supported in relation to the extractor device.
9. A tack extracting machine having a rotary extractor device consisting of a pair of circular plates clamped together face to 70 face with an intervening space, channels in the opposing faces, said channels lying on chords of the plates and of the plates conjointly forming passages between the plates for extracting the tacks, and a guard member 75 partly surrounding the rotary extractor device mounted in a spring controlled manner and arranged to yield relatively to the said device by an oscillating movement.
10. A tack extracting machine having a 80 rotary extractor device consisting of a pair of circular plates clamped together face to face with an intervening space, channels in the opposing faces, said channels lying on chords of the plates and of the plates 85 conjointly forming passages between the plates for extracting the tacks, and a guard member partly surrounding the rotary extractor device mounted in a spring controlled manner and arranged to yield relatively to the 90 said device by a vertical movement.
11. A tack extracting machine having a rotary extractor device consisting of a pair of circular plates clamped together face to face with an intervening space, channels in 95 the opposing faces, said channels lying on chords of the plates and of the plates conjointly forming passages between the plates for extracting the tacks, and a guard member partly surrounding the rotary extractor device mounted in a spring controlled manner and arranged to yield relatively to the 100 said device by an oscillating and a vertical movement.
12. A tack extracting machine having a 105 rotary extractor device consisting of a pair of circular plates clamped together face to face with an intervening space, channels in the opposing faces, said channels lying on chords of the plates and of the plates 110 conjointly forming passages between the plates for extracting the tacks, a guard member partly surrounding the rotary extractor device mounted in a spring controlled manner and arranged to yield relatively to the 115 said device, and adjustable means to limit the extent of said yielding movement.

In testimony whereof I affix my signature in presence of two witnesses.

EDWARD PERCY CORPS.
